UNITED STATES PATENT OFFICE.

MARLEY FOTHERINGHAM HAY AND CORNELIUS EKAMA, OF THE HAGUE, NETHERLANDS.

APPARATUS FOR MOVING DIVING-RUDDERS OF SUBMARINES.

1,216,564.

Specification of Letters Patent.

Patented Feb. 20, 1917.

Application filed September 10, 1915. Serial No. 50,010.

To all whom it may concern:

Be it known that we, MARLEY FOTHERINGHAM HAY, a subject of the King of England, residing at Carel van Bylandtlaan 4, The

5 Hague, Netherlands, and CORNELIUS EKAMA, a subject of the Queen of the Netherlands, residing at Willemstraat 71, The Hague, Netherlands, have invented certain new and useful Improvements in Apparatus for 10 Moving Diving-Rudders of Submarines; and we do hereby declare the following to be a full, clear, and exact description of the invention, such as will enable others skilled in the art to which it appertains to make 15 and use the same.

This invention relates to an apparatus for operating the diving rudders or hydroplanes of submarines by means of which it is possible to set such rudders in any suitable position when the boat is submerged and which 20 allows the rudders to be stored in the superstructure of the boat when the said boat is running on the surface of the water.

For enabling the rudders to be set into 25 different positions for diving purposes, they are connected to the ends of a shaft, which shaft is mounted transversely across the hull of the boat, so that by turning the shaft the rudders can be brought into any 30 required position. To enable the rudders to be stored in the superstructure of the boat, they are pivotally mounted upon studs fixed to the end of the said shaft, the axis of these studs being perpendicular to the 35 axis of the shaft, so that when the said shaft is turned to bring the rudders into a horizontal position, such rudders can be moved in their own plane so that they pass through a slotted opening in the side wall 40 of the superstructure and are brought into a space formed for their reception above the hull of the boat.

The accompanying drawing shows one method of carrying out the invention.

45 Figure 1 is a vertical cross section through the axis of the shaft of the apparatus forming the subject of the invention.

Fig. 2 is a top plan of the apparatus.

50 1 are the rudders which in the drawing are shown in full lines in the stored position, and in dotted lines in the working position. 2 is the hull of the boat, provided with a superstructure the side walls of which are indicated by 3. A shaft formed in two 55 pieces 4 and 5, is provided extending trans-

versely across the boat. The pieces 4 and 5 are connected together by a flanged coupling 6 and supported by the bearings 7, 8, 9 and 10 fixed to the hull 2.

At the outer ends of the shaft 4, 5 are 60 provided eyes 11, over which fork-shaped portions of the rudders 1 engage. Through the eyes 11 and the fork-shaped portions are passed studs 12 so that the rudders 1 can be moved relatively to the shaft 4, 5. 65

When the rudders 1 are set in the working position, that is to say in the position indicated by dotted lines in both the figures, they may be turned into different directions for diving purposes by rotating the shaft 70 4, 5 by means of a lever 13, connected to links 14 (Fig. 2) which can be operated from the control station inside the boat.

The mechanism for turning the rudders upon the studs 12 is so constructed that it 75 does not interfere with the rotation of the shaft 4, 5.

The mechanism comprises a sliding sleeve 15 which can move along a key 16 on the part 5 of the shaft. This movement is effected by means of a threaded spindle 17 upon which works a traveling nut 18. The traveling nut 18 is connected to a slip ring 19 which lies within a groove in the sliding sleeve 15. The spindle 17 is rotated by 80 85 means of bevel gearing 20, 21 from a shaft 22, operated from the control station, so that the sliding sleeve 15 can be moved along the portion 5 of the shaft.

At each side of the sliding piece 15 are 90 provided projecting arms 23 and 24, having pivoted to their ends links 25 and 26. The link 25 is connected by means of an arm 27 to the larboard rudder while the link 26 is directly connected to the starboard rudder 95 by means of an eye 28.

The mechanism for moving the sliding sleeve 15 also could be obtained by using a lever, on a vertical shaft, and connected by two links to two pivots on the top and under side of the slip ring 19, the operating of the lever from the inside of the boat giving the stroke necessary for moving the rudders in or out, the mechanism being so arranged that in the working position of 100 105 the rudders the operating lever and the connecting links are in locked position.

When the sliding sleeve 15 is moved, owing to the rotation of the shaft 22, this causes the larboard diving rudder to be 110

pulled outward and the starboard diving rudder to be pushed outward, the horizontal movement of such rudders being limited by the sliding sleeve 15 coming into contact with the surface of the support 10 as shown in dotted lines at Fig. 2.

In the working position of the diving rudders, the diving movement as previously stated is obtained by operating the lever 13, the sliding sleeve 15 turning at the same time freely in the slings 19. In the stored position of the diving rudders the sliding sleeve 15 comes against the surface of the bearing 9. Owing to the friction between the screw and nut connection 17, 18, in whatever position the mechanism is set, security is automatically obtained.

What we claim and desire to secure by Letters Patent of the United States of America is:—

1. Operating mechanism for the diving rudders of submarines comprising a shaft located transversely with respect to the hull of the boat and adapted to be controlled from the interior thereof, a diving rudder pivotally mounted at each end of the said shaft and in such a way that the pivotal axis is perpendicular to that of the shaft, and means for turning the said rudders upon their pivots for the purposes set forth.

2. Operating mechanism for the diving rudders of submarines comprising a shaft located transversely with respect to the hull of the boat and adapted to be controlled from the interior thereof, a diving rudder pivotally mounted at each end of the said shaft and in such a way that the pivotal axis is perpendicular to that of the shaft, means for turning the said rudders upon their pivots, and slotted openings in the superstructure of the boat so located and arranged that the said diving rudders can pass through said openings into a space formed for their reception above the hull of the boat or be protruded and brought into the operating position when required substantially as described.

3. Operating mechanism for the diving rudders of submarines comprising a shaft located transversely with respect to the hull of the boat and adapted to be controlled from the interior thereof, a diving rudder pivotally mounted at each end of the said shaft and in such a way that the pivotal axis is perpendicular to that of the shaft, means for turning the said rudders about their pivots, such means consisting of a part adapted to be moved from the interior of the boat the said part controlling by its motion link mechanism for bringing the rudders into their extreme positions substantially as described.

4. Operating mechanism for the diving rudders of submarines comprising a shaft located transversely with respect to the hull

of the boat and adapted to be controlled from the interior thereof, a diving rudder pivotally mounted at each end of the said shaft and in such a way that the pivotal axis is perpendicular to that of the shaft, means for turning the said rudders about their pivots, such means consisting of a sleeve slidable, but not rotatable upon, the shaft, links attached to projecting arms in connection with the said sleeve, one of such links being pivoted to one of the rudders and the other being pivoted to an arm controlling the movements of the other rudder, a threaded spindle rotatable from the interior of the boat, a nut traveling upon such spindle, and a slip ring connecting the said nut to the sliding sleeve, all substantially as described.

5. Operating mechanism for the diving rudders of submarines, comprising a shaft formed in two portions, connected together by a coupling, the said shaft being mounted in bearings upon and located transversely with respect to the hull of the boat and being adapted to be controlled from the interior thereof, a diving rudder pivotally mounted at each end of the said shaft, slotted openings in the superstructure of the boat, so located and arranged that the said rudders can pass through such openings into a space formed for their reception above the hull of the boat, or be protruded and brought into the active position, and means for bringing the said rudders into the two extreme positions, such means consisting of a sleeve slidable, but not rotatable upon, the shaft, links attached to projecting arms in connection with the said sleeve, one of such links being pivoted to an arm controlling the movements of the other rudder, a threaded spindle rotatable through bevel gearing from the interior of the boat, a nut traveling upon such spindle, and a slip ring connecting the said nut to the sliding sleeve all substantially as described.

6. Operating mechanism for diving rudders of submarines, comprising a shaft formed in two portions, connected together by a coupling, the said shaft being mounted in bearings upon and located transversely with respect to the hull of the boat and being adapted to be controlled from the interior thereof, a diving rudder pivotally mounted at each end of the said shaft, slotted openings in the superstructure of the boat, so located and arranged that the said rudders can pass through such openings into a space formed for their reception above the hull of the boat, or be protruded and brought into the active position, and means for bringing the said rudders into the two extreme positions, such means consisting of a sleeve slidable, but not rotatable upon, the shaft, links attached to projecting arms in connection with the said sleeve, one of such

links being pivoted to one of the rudders and the other being pivoted to an arm controlling the movements of the other rudder, a lever on a vertical shaft, connected by two links to two pivots on the top and under side of the slideable sleeve, the operating of the lever from the inside of the boat giving the stroke necessary for moving the rudders

and so arranged that in the working position of the rudders the operating lever and 10 the connecting links are in locked position, all substantially as described.

In testimony whereof we affix our signatures.

MARLEY FOTHERINGHAM HAY.
CORNELIUS EKAMA.
